UNITED STATES PATENT OFFICE

EDMUND A. SPRUNG, OF DETROIT, MICHIGAN

GRINDING FIXTURE

Application filed April 13, 1929. Serial No. 354,799.

The present invention pertains to a novel fixture for supporting work such as valves, drills or any other objects of like character and nature, in a position facilitating their being ground by portable hand operated grinding machines or power driven grinding machines.

As a primary object my invention aims to devise a work supporting fixture adaptable to both hand operated and power driven grinding wheels, which fixture supports a valve of the type employed in an internal combustion engine in the proper angle of contact with the grinding wheel and permits and facilitates its rotation while in contact with the grinding surface. The device is designed so that it supports the valve stem in such a manner that the valve head may be ground at the true angle desired providing the state of the stem which commonly is known to become warped after being used for a period of time is not contorted to such as extent that grinding would be impractical.

Another object of my invention is to devise a fixture for supporting work in conjunction with a hand operated portable grinding wheel which will facilitate the grinding of the valves used in the internal combustion engine in a boat, which valves have become defective while on a cruise. This feature obviously overcomes a great inconvenience found in cruising when the valves become defective and it becomes necessary to enter the nearest port with the likelihood that there will be no equipment at the port suitable for grinding the valves. A device of this character becomes of inestimable value while cruising through uninhabited parts and when it becomes necessary to travel for miles in order to reach a point where the defect in the valves may be corrected.

With these and other objects in view my invention is thereafter set forth and more particularly pointed out in the appended claim, reference being had to the accompanying drawings, in which

Figure 1 is a top plan view of my invention attached in the proper relation to a hand operated grinding wheel;

Figure 2 is a broad-side elevation of the

work supporting fixture attached to a bench or other supporting means;

Figure 3 is an end view of the work supporting fixture;

Figure 4 is a top plan view of my invention illustrating the manner of installation relative to a power driven grinding wheel;

Figure 5 is a side elevation of my invention as equipped to a power driven grinding wheel; and

Figure 6 is an alternative device for supporting the work.

Like characters are employed to designate the corresponding parts throughout.

The numeral 1 indicates a hand operated grinding wheel, which may be of any conventional type, supported upon a convenient work bench 2 by the usual clamping members supplied as part of the device. In conjunction with a wheel of this type I supply a work supporting fixture comprising a post 3 formed with a base member 4 having a slot 5 through which a screw or bolt 6 is passed and inserted in the bench 2 for securing the post 3 to the latter. This manner of attachment permits adjustable movement of the post 3 by loosening the screw 6 so that the post may be located at the desired point in the proper spaced relation to the wheel 1.

The post 3 is drilled longitudinally as at 7 to support a bolt 8 which is inserted therein and a screw 9 is threaded in the post to engage the bolt 8 so that by tightening the screw 9 the bolt is frictionally held in any desired vertical position in the drilled bore 7 by the screw 9 which, however, does not positively prevent rotary movement and therefore exerting rotary pressure through the members which are described as the description progresses is a simple procedure due to the manner in which the said members serve as a lever and the bolt 8 may be rotated in a manner and for the purpose which later becomes apparent. The upper end of the bolt 8 extends above the post 2 and is provided with a head 10 formed with ears 11 to extend upwardly and spaced to receive the ear 12 projecting downwardly from the underside of the block 13.

The block 13 is substantially rectangular

in shape and has a groove 14 formed on the upper side thereof. Screws 15 are received in the block and extend through drilled holes 16 in bars 17, coiled springs 18 being provided to surround the screws 16 and exert pressure between the block 13 and the bar 17 whereby the latter is held abutting the head of the screw. The opposite end of the bar 17 is slotted as at 19 to receive a screw 20 screwed into the head 13 and having the upper end provided with an integral head 21 in the nature of a wing nut. The underside of the bars 17 are provided with downwardly extending lugs 22 which are formed with grooves 23 of like nature and opposing the groove 14. The valve which is to be ground is laid with the stem 24 resting in the groove 14 in the head 13 and the bars 17 are then swung upon the screws 15 so that they lie transversely over the stem in which position the slot 19 partially surrounds the screw 20 so that by tightening the latter the lug 22 having the groove 23 is moved into contact with the upper side of the valve stem 24. The block 25 is then swung radially by means of the bolt 8 in the bore 7 so that the valve head 25 is brought into contact with the grinding wheel 1 while the axis of the stem is lying at an angle of 45° to the axis of the wheel. The valve head is then swung away from contact with the wheel and the screws 15 and 20 are tightened to maintain the stem in this position while a handle 26 is placed over the end of the stem for the purpose of rotating the stem.

The handle 26 has a circular hub adapted to surround the valve stem and is provided with a set screw 27 extending radially through the hub to engage the valve stem so that rotation of the handle rotates the valve. The handle 26 is moved on the stem towards the head until the screw 28 extending through the hub engages against a washer 28' which in turn engages the end of block 13 and then the screw 26 is tightened to engage the stem. This leaves the valve supported so that it may be swung into contact with the wheel to permit the head being ground at 45°, the amount which is to be ground off being determined by slight rotation of the screw 28 whose end is in contact with the block 13, the turning of the screw causing the valve stem to be moved longitudinally.

To obtain the proper 45° angle it might be found advisable to graduate the upper end of the post 3 and the head 10 or the bolt 8 by markings which will indicate the angle which the valve head is being grooved. By supplying a pivotal connection between the block 13 and head 10 by means of the ears 11 and 12 through which a bolt 29 is passed it becomes possible to obtain a contact with the periphery of the wheel which will grind at 45°. It is also found desirable at times to graduate the ears 11 and 12 so that the block 13 may be

definitely secured with the groove 14 on a parallel plane to the axis of the wheel 1 or in other words parallel to the surface of the supporting bench.

In Figures 4 and 5 a power driven grinding wheel is provided and mounted upon a conventional stand having a rod 30 supported by arms 31 attached to the supporting frame. To mount the present fixture to a wheel showing these characteristics the lower end of the post 3 is provided with a pivoted connecting means 32 and a bolt 33 for clamping the post to the rod 30.

In Figure 6 is illustrated an alternative device for receiving the stem 24 of the valve which comprises two blocks 34 and 35, the block 35 having an ear 36 to be received between the ears 11 on the head 10, and also having a drilled hole 37 to accommodate the bolt 29. The blocks are provided with semi-circular grooves 38 and 39 which combine to form circular openings of different sizes to accommodate valves having stems of varying diameters. The two blocks are secured together by screws 40 provided with wing nuts 41, a portion of each block being bored to receive coiled springs 42 adapted to force the blocks apart when the thumb screws 41 are released.

By experimentation it has been found that a greater smoothness and regularity in grinding the valve head is attained by employing a rod 42, received in a drilled boss 43 on the lower side of the head 13, the rod being held in any desired position by a set screw 44, this being clearly illustrated in Figure 2 of the drawings. The rod 42 is provided with a goose-neck 45 and a bent back portion 46 upon which is slidably mounted a sleeve 47, backed by a spring 48 which exerts pressure outwardly on the sleeve. The rod 42 is held by the set screw so that the sleeve 47 is in contact with the valve head 25 with the spring 48 slightly compressed whereby the sleeve exerts resilient pressure against the valve head. This construction providing the resilient pressure against the valve head tends to prevent vibration of the valve head while it is in contact with the grinding wheel and permits a smoother ground surface to be obtained.

It becomes apparent from the description that the fixture for supporting the work is of such nature and qualification that it may be employed in factory or workshop without interfering with the ordinary use of the grinding wheel. Its most desirable feature is, however, that it may be conveniently carried in a boat to be used in case of an emergency in which it is found necessary that the valves should be ground while on a cruise.

The device is illustrated and described as a fixture for grinding valves for internal combustion engines, but it is not limited to that use alone as it may also be used for supporting various other articles at grinding angles.

Specific structural embodiments have been illustrated and described but it is to be understood that various alterations may be made in the details of construction without departing from the spirit of my invention as depicted in the appended claim.

5 What I claim is:—

The combination with a grinding wheel, of a vertically extending post adjustably secured in spaced relation thereto, a grooved block mounted to swivel and rotate on said post, adjustable work retaining members on said block adapted to engage the stem of a valve to secure the latter thereon, a goose neck rod adjustably secured to the bottom of said block to extend outwardly beyond the head of said valve, a sleeve slidably mounted on a portion of said rod that is bent back towards said valve head, and a spring surrounding a portion of said rod and engaging said sleeve in a manner to force it into contact with said valve head.

10 In testimony whereof I affix my signature.

EDMUND A. SPRUNG.
